UNITED STATES PATENT OFFICE.

RAYMOND CALPIN, OF EVERETT, MASSACHUSETTS, ASSIGNOR TO A. S. CAMPBELL COMPANY, OF EAST BOSTON, MASSACHUSETTS, A CORPORATION OF MASSACHUSETTS.

CURTAIN WINDOW.

Application filed April 14, 1923. Serial No. 632,107.

This invention pertains to improvements in curtain windows. It is among the objects of the invention to provide a curtain window having a frame adapted to be secured to the carrying fabric by prongs, while at the same time a pleasing appearance and a firm engagement are provided, an objectionable tearing of the fabric adjacent the prongs being eliminated.

In the drawings, which show preferred forms of my invention:

Figure 1 shows a curtain window assembled with its carrying fabric;

Fig. 2 is a section on the line 2—2, on a larger scale and partially broken away, being partly in elevation;

Figs. 3, 4 and 5 are sections showing various stages of assembling the window;

Figs. 6 and 7 show plan and side elevations of a section of a frame part prior to assembly;

Fig. 8 is a section on the line 8—8 of Fig. 1, showing a preferred construction for relieving the curtain of the weight of the window by suspension means;

Fig. 9 is a detail section of a modified form of my invention;

Fig. 10 is a section through a frame, from which the bead for securing the covering plate is omitted, being a somewhat cheaper construction than where such cover plate is provided for; and

Fig. 11 is a fragmentary view of the installation showing the formation of the prong-concealing flange at the sides and at one corner of the installation.

Referring to the drawings, I have shown (Fig. 2) a flexible carrier for the window, herein typified by the curtain material 11 to which are secured at its opposite sides frame elements secured together and to the fabric by prongs. The glass 13 is held between these frame elements, the offset portion 14 of one of the prong-receiving frame elements 15 providing a recess into which the glass fits, preferably cushioned by cushioning means 16 which may be adhesive tape folded to fit the edge of the glass and preferably cemented to the adjacent frame and curtain material. Further cushioning of the glass is provided by the curtain material 11 adjacent the glass-receiving aperture, indeed, the curtain material opposite the glass is preferably not removed until after the curtain window installation is otherwise

completed, at which time a sharp knife may be guided along the interior edge of the frame 17, cutting out the undesired curtain material and at the same time trimming off any projecting edges of the adhesive tape or other cushion 16.

The frame 17, which provides the prongs 12 of which a great number are provided, is preferably formed from a single sheet of metal, while providing a relatively extended area to press against and hold firmly the curtain material, and at the same time locating the prongs 12 a very considerable distance from either edge of the frame. I accomplish this by bending the material of which the frame is made double, preferably at both sides thereof to provide nicely furnished exterior and interior edges to the finished frame, also increasing the strength thereof, and by providing the prongs intermediate the edges on the interior surface of the frame, the prongs preferably struck from the material lying toward the central portion of the sheet from which the frame is made. The frame 17 preferably also provides one or more stiffening ribs or beads, shown as single in Figs. 2, 3, 4, 5 and 8 and as double in Fig. 10. Where the material is to be folded over the prong-providing frame, as shown in Fig. 9 or where the stiffening rib is provided by the prong-receiving frame, as shown in Fig. 7 of my co-pending application filed herewith, the stiffening rib may be omitted from the prong-providing frame. In any case, however, to obtain the most satisfactory grip of the curtain material and glass, the prongs, while on the interior of the frame 17, should be supported by the outer surface thereof to increase the support of the prong, and to this end I have avoided locating the prongs 12 in a plane passing through the hollow portions of the stiffening rib behind it. The glass-receiving recess is shown as entirely within the frame on the side of the fabric where the glass is located, instead of entirely in the opposite frame, or instead of partly in one frame and partly in the other, this construction affording advantages in assembly and also in affording a superior grip on the fabric. I prefer, as shown, to provide the prong on that frame which is on the opposite side of the fabric from the glass, though for some purposes a reversal may be desirable, as for instance in the modification shown in Fig. 7 of

my co-pending application Serial No. 632,108 filed herewith.

In Figs. 2, 5, 8 and 9, I have shown the frame 15 provided with a peripheral bead 18, which may be relatively narrow and formed when the frame is stamped. Over this peripheral bead, a cover frame 19 may be snapped after completion of the curtain window installation, thereby to present a very finished and pleasing appearance. A cheaper and equally satisfactory construction is shown in Fig. 10, wherein the bead 18 is provided only at the "corners" or rounds of the frame, the intermediate portions provided with flanges 19 adapted to be bent inwardly to conceal the prongs, and incidentally to stiffen the frame, the bending performed as a part of the assembly as indicated in Figs. 3 and 4.

In Fig. 1, I have shown the window provided with three supporting straps 20, and in Fig. 9, I have shown a section through the point of connection of one of these straps to the frame, the strap 20 lying against the curtain material 11 and passing through a slot in the bead 18, being pierced and held by a prong 12.

Where the separate cover plate is supplanted by the cover flange 19 as in Fig. 10, the prongs 12 and the corresponding holes 30 may be omitted adjacent the "corners" or rounds, so that no fastening means will be visible after the cover flange is bent and pressed into its final position.

Where it is desired to replace a broken glass, this may be done very easily pursuant to removal of the cover frame, or pursuant to bending up of the cover flange 19, as the case may be, this rendering accessible the prongs 12, which may be straightened to permit disassembly, after which assembly with the new glass is but a repetition of the original assembling operation.

While I have shown and described preferred forms of my invention, it will be understood that considerable changes may be made without departing from the scope of my invention, which is best defined in the following claims.

I claim—

- 50 1. A curtain window frame including two opposed parts adapted to receive between them a curtain and a glass, one of said frame parts presenting an extended substantially uninterrupted flat surface in contact with the curtain material and presenting at points considerably removed from both edges thereof, a plurality of prongs each passing through the curtain material and the opposed frame part to clamp said frames 55 against a substantial portion of said curtain, said one of said frame parts including a single sheet of metal having reversely bent opposite edges and said prongs projecting from said frame part between said edges.
- 60 65 2. A curtain window frame including two

opposed parts adapted to receive between them a curtain and a glass, one of said frame parts presenting an extended substantially uninterrupted flat surface in contact throughout substantially the entire width thereof with the curtain material and presenting at points considerably removed from both edges thereof, a plurality of prongs each passing through the curtain material and the opposed frame part, said one of said frame parts formed of sheet metal having reversely bent flanges at its edges, said prongs projecting from the inside of the frame part adjacent to the free ends of the reversely bent flanges.

3. A curtain window frame including two opposed parts adapted to receive between them a curtain and a glass, one of said frame parts presenting an extended substantially uninterrupted flat surface in contact with the curtain material and presenting at points considerably removed from both edges thereof, a plurality of back-supported prongs each passing through the curtain material and the opposed frame part whereby to clamp the curtain between said extended surface and the opposed frame, said frame part providing said prongs also providing one or more stiffening ridges.

4. A curtain window frame part presenting a sheet of metal reversely bent from at least one edge to provide a double thickness, and a part presenting prongs projecting from the inner portion of the frame part adjacent the inner edge of the reversely bent portion, the outer portion providing a hollow stiffening rib and said prongs out of line with the hollow in said rib so as to be back-supported by the outer portion of said frame part.

5. A curtain window installation including two opposed frame parts on opposite sides of the curtain fabric and the window glass, one of said frame parts having an extended surface in contact with the curtain fabric substantially throughout its width and presenting prongs considerably removed from either edge thereof penetrating the curtain fabric and clenched over the opposed frame part thereby securely to grip the curtain and glass between said parts and a prong-concealing flange bent into place after said prongs are clenched.

6. A curtain window frame including a prong-presenting frame element and a prong-receiving and glass-positioning frame element, said second-mentioned frame element pressed from sheet metal and presenting in cross-section a relatively wide curtain-engaging base portion having a plurality of prong-receiving slots extending therethrough and a prong-concealing flange adapted to be bent in from the outer edge of said base portion to conceal the prongs presented by said prong-presenting frame

- element after the prongs have penetrated the curtain and the second-mentioned frame element, and have been clenched against said base.
6. 7. A curtain window part presenting a glass-receiving offset flange, a relatively flat curtain-engaging surface and an outer edge bent back on itself to conceal cooperating frame-securing elements, said bent back edge narrow adjacent the corners of the frame while of substantial width at the straight portion of the frame.
8. A curtain window part presenting a glass-receiving offset flange, a relatively flat curtain-engaging surface and an outer edge bent back on itself to conceal cooperating frame-securing elements, said bent back edge pre-formed and narrow adjacent the corners of the frame while bent during assembly and of substantial width at the straight portion of the frame.
9. A curtain window installation comprising a prong-providing frame and a prong-receiving frame, said prong-providing frame presenting a relatively extended flat inner surface and formed of material doubled back on itself to present a continuous exterior, the prongs projecting from said frame intermediate the edges, said prong-receiving frame presenting a glass-receiving offset, a relatively extended curtain-engaging portion perforated to admit passage therethrough of said prongs and having associated therewith bendable covering means for concealing said prongs pursuant to assembly with the curtain and the glass, the curtain material overlapping the glass at that side thereof adjacent the prong-providing frame.
10. A curtain window installation comprising a prong-providing frame and a prong-receiving frame, said prong-providing frame exteriorly ribbed and presenting a relatively extended flat inner surface formed of material doubled back upon itself from each edge, and presenting a continuous exterior surface, the prongs being located at the edge of one of said doubled-back portions, said prong-receiving frame presenting a glass-receiving offset, a relatively extended curtain-engaging portion perforated to admit passage therethrough of said prongs and having associated therewith bendable flange means for concealing said prongs pursuant to assembly with the curtain and the glass.
11. A curtain window installation comprising a pair of cooperating frame parts located on opposite sides of a curtain and window glass, one of said parts presenting a glass carrying seat and a relatively wide flange engaging the curtain, the other frame part presenting integral securing elements projecting through and bent against said flange to hold the frame parts in clamped relation to the curtain and glass, the outer edge of said flange bent back over the ex-
- posed ends of said securing elements to produce a finished appearance.
12. A curtain window installation comprising a pair of cooperating frames arranged on opposite sides of the curtain and window glass, each having a flat curtain gripping surface of substantial width bearing directly against opposite sides of the curtain, one of said frames presenting a back-supported prong-presenting portion, the other frame perforated intermediate the edges of the curtain engaging surface to receive said prongs, said prongs clenched over said perforated frame, said other frame having a flange bent down to conceal the exposed ends of said prongs after bending said prongs, thereby producing a finished appearance.
13. A curtain window installation comprising a pair of opposed sheet metal frame parts adapted to be secured to the curtain fabric and to grip a window therebetween, one of said parts presenting an outer strengthening bead between its edges and a relatively flat prong carrying portion extending across the channel in said bead, prongs struck up from said portion and having their backs supported against the outer portion of said frame part adjacent the edge of the bead channel, the other frame part having a curtain engaging surface opposite said first mentioned frame part and presenting openings to receive said prongs, said prongs clenched down over said frame part, and flange means associated with said other frame part to conceal the clenched down portions of said prongs and to strengthen said frame part.
14. A curtain window frame comprising a prong-providing portion and a prong-receiving portion, each presenting extended surfaces for gripping the curtain fabric therebetween, said prong-receiving portion presenting in cross-section a glass-overlying flange, a base flange presenting one of said extended surfaces, a glass-surrounding flange connecting said glass overlying flange and said base flange, and a prong-concealing flange bent inwardly from the outer edge of said base flange.
15. A curtain window frame comprising a prong-providing portion and a prong-receiving portion, each presenting extended surfaces for gripping the curtain fabric, said prong-receiving portion presenting in cross section a glass-overlying flange, a glass-surrounding flange, a base flange presenting one of said extended surfaces and a prong-concealing flange bent inwardly from the outer edge of said base flange and terminating adjacent the junction of said glass-surrounding flange and said base flange.
16. A frame portion for curtain window installations presenting a piece of metal turned back on itself at each side to present rounded edges, a relatively flat back-sup-

ported interior surface and back-supported prongs projecting therefrom, and a plurality of strengthening beads on its exterior surface.

5 17. A frame portion for curtain window installations presenting a piece of metal turned back on itself at each side to present rounded edges, a relatively flat interior sur-

face and prongs projecting therefrom, and a plurality of strengthening beads on its exterior surface, a flat portion between said beads overlying and back-supporting the bases of said prongs.

In testimony whereof, I have signed my name to this specification.

RAYMOND CALPIN.
